UNITED STATES PATENT OFFICE.

GEORGE W. GANTT, OF MOUNT AIRY, NORTH CAROLINA.

STONEWORKING-MACHINE.

1,203,527.

Specification of Letters Patent. Patented Oct. 31, 1916.

Application filed October 9, 1915. Serial No. 55,032.

To all whom it may concern:

Be it known that I, GEORGE W. GANTT, a citizen of the United States, residing at Mount Airy, in the county of Surry and State of North Carolina, have invented certain new and useful Improvements in Stone-working Machines; and I do hereby declare the following to be a full, clear, and exact description of the invention, such as will 5 enable others skilled in the art to which it appertains to make and use the same.

The invention relates to improvements in stone working machines.

The object of the present invention is to 15 improve the construction of stone working machines and to provide a simple, practical and comparatively inexpensive device designed for supporting and carrying pneumatic hammers and adapted to enable the 20 same to be readily moved over the faces of stone for dressing the head, sides and top thereof whereby a stone may be worked from the rough to the finished form.

A further object of the invention is to 25 provide a stone working machine of this character equipped with means for mounting a pneumatic tool for oscillatory movement in a vertical plane and also for a similar movement in a horizontal plane and adapted to 30 automatically counterbalance the tool operating in the vertical plane so that the same may be adjusted toward and from the supporting means and oscillated at any desired adjustment without affecting the counterbalancing means.

A further object of the invention is to 40 provide a stone working machine adapted to be rotated to arrange its operating mechanism at different points for operating on stone plates in different positions around the machine so that the machine may be arranged in operative position with relation to such stones without moving either the entire machine or the stone.

45 With these and other objects in view the invention consists in the construction and novel combination and arrangement of parts hereinafter fully described, illustrated in the accompanying drawings and pointed out in 50 the claims hereto appended, it being understood that various changes in the form, proportion and minor details of construction may be resorted to without departing from the spirit or sacrificing any of the advantages of the invention.

In the drawings Figure 1 is an elevation

of a stone working machine constructed in accordance with this invention, Fig. 2 is a vertical sectional view, partly in elevation taken at right angles to Fig. 1, Fig. 3 is a 60 plan view partly in section, Fig. 4 is a horizontal sectional view on the line 4—4 of Fig. 2, Fig. 5 is a detail sectional view on the line 5—5 of Fig. 2, Fig. 6 is a detail horizontal sectional view on the line 6—6 of Fig. 1. 65

Like numerals of reference designate corresponding parts in the several figures of the drawings.

In the accompanying drawings in which is illustrated the preferred embodiment of 70 the invention, the stone working machine comprises in its construction, a base 1 preferably of rectangular form provided with a central bearing 2 having a vertical socket 3 for the reception of the lower end 4 of a 75 vertical standard or post 5 which is adapted to rotate in the bearing to arrange the parts carried by it at different points around the base so as to operate on stones in different 80 positions around the machine thereby enabling a plurality of stones to be worked or dressed without moving the machine bodily or transferring the stone from one point to another. The standard 5 is provided adjacent to its lower end with a square or enlarged portion 6 adapted to rest upon the upper rest or end of the bearing for supporting the standard clear of the bottom wall thereof. Any suitable anti-friction device 85 may of course be employed in the bearing 90 if desired. The standard is locked in its adjustment by means of a sliding key 7 operating in a groove 8 of the standard 5 and adapted to engage any one of a plurality of grooves 9 of the bearing 2. The grooves 95 are arranged vertically and the sliding key is adapted to be readily moved into and out of engagement with the grooves of the bearing to permit the standard to be rotated and also to lock the standard in its adjustment. 100 Any number of grooves may of course be provided and any other suitable means may of course be employed for holding the standard against rotary movement and for permitting rotary adjustment of the standard. 105

The standard is provided at its upper portion with an arm 10 composed of side pieces 11 and an inclined bar or member 12 secured between the side pieces 11 and having its lower end fitted against the standard in a 110 recess 13 formed in an elongated squared portion of the said standard, the enlarged

or squared portion 14 is provided with a guide opening 15 arranged in horizontal alinement with a guide 16 of the arm 10 and receiving a slidable rack bar 17. The 5 guide 16 is preferably formed by an opening in the vertical portion of the inclined bar 12. The rack bar is provided in its lower face with a groove 18 and it has teeth 19 at the top wall thereof to mesh with a pinion 20 mounted between the side pieces 11 and arranged on a shaft 21. The shaft 21 carries a gear wheel 22 which meshes with a pinion 23. The pinion 23 is provided with a crank handle 24 and it is locked 15 against rotary movement by a pawl or dog 25 pivotally mounted on the adjacent side piece 11 and having a weighted engaging portion which is held in engagement with the pinion 23 by gravity. By rotating the 20 pinion 23 the rack bar is moved inwardly or outwardly to arrange a pivoted oscillatory casing 26 in the desired position.

The casing 26 which has spaced side plates 27 is provided with a horizontal rod 28 extending through a longitudinal bore 29 of the rack bar and provided with a threaded outer end 30 for the reception of a nut 31 for detachably securing the rod in the bore or opening of the rack bar. The rod 28 30 forms a pivot for the casing 26 which is adapted to be turned at different angles or inclinations and as the casing rotates on a horizontal axis it is adapted to be turned to various inclinations at either side of a 35 perpendicular position. The casing 26 is equipped with inner and outer flanged guide rollers 32 and 33 arranged in pairs at the inner and outer portions of the casing and receiving an automatically adjustable counterbalancing bar 34 and a slidable tool carrying bar 35. The bars 34 and 35 which are simultaneously movable in opposite directions are provided with teeth 36 and 37 arranged in grooves 38 and 39 and meshing 40 with an interposed gear wheel 40. The gear wheel 40 or pinion meshes with the teeth of the rack bars 34 and 35 and is mounted on a shaft or spindle 41 which is journaled in the side plate 27 of the casing 26. The slidable 45 tool carrying rack bar 35 is provided at its outer end with a head 42 having secured to it a plate 43 provided with a flange 44 and equipped with bolts 45. The flange of the head is provided with an opening to receive 50 the casing or cylinder 46 of a pneumatic hammer or tool which is retained in the opening by the said bolts 45. Any form of pneumatic tool may of course be employed and various tools may be operated for working 55 a stone in the rough and for the various operations of dressing the stone. Also any other suitable tool or device for operating on a stone may be carried by the slidable rack bar 35 which is adapted to be oscillated 60 to move the tool over a stone. The plate 43

is provided with a suitable handle 44 to facilitate the operation of the machine. The slideable counterbalancing bar 34 is equipped at its outer end with a slideably mounted adjustable weight 48 adapted to 70 counterbalance the weight of a pneumatic tool and after the tool has been properly counterbalanced it will be maintained in its adjustment by the gearing which will cause the tool to be readily moved inwardly and 75 outwardly with respect to the supporting means when pressure is applied to the rack bar 35 by the operator.

The rounded portion of the standard has mounted a vertically adjustable casing 49 80 having spaced side plates and provided with a central vertical sectional bearing 50 receiving the vertical standard. The casing is provided with spaced upper and lower rollers 51 arranged in pairs and receiving 85 a slideable tool supporting frame or carrier 52 arranged between the rollers 51 and composed of spaced longitudinal bars 53 connected at the front end of the carrier by a head 56 having an opening formed in a 90 flange 57 and adapted to receive a pneumatic tool which is arranged in a vertical position for operating upon the upper face or top of the stone. The head 56 is equipped with a suitable handle 58 similar to the 95 handle of the oscillatory slideably mounted rack bar.

The casing 49 which is adapted to be raised and lowered is equipped with hoisting mechanism consisting of a hoisting rope 100 or cable 59 arranged on a pulley 60 and attached at one end at 61 to the casing and at its other end to a windlass drum 62 journaled in the casing 49 at one end thereof and equipped with a ratchet wheel 63 provided 105 with a crank handle 64 and engaged by a pivoted pawl or dog 65 for locking the casing 49 in its vertical adjustment. The roller 60 is journaled in a bifurcated bearing bracket 66 having a rounded lower portion or pivot 67 arranged in a bearing socket 68 in the upper end of the standard. The slideable frame is adapted to be raised and lowered by means of the casing and the hoisting mechanism and it is also capable of permitting the tool carrying frame to slide inwardly and outwardly and to be oscillated horizontally to operate over the different 110 portions of the top of a stone.

What is claimed is:—

1. A stone working machine including a slideable bar arranged horizontally and movable inwardly and outwardly, means for supporting the same, an oscillatory support carried by the said bar and freely movable on a 125 horizontal axis, and a slideable tool supporting bar mounted on the said support and movable freely transversely of the axis thereof, said tool supporting bar being provided at the outer end with means for holding a 130

tool at an angle to the same whereby the tool may be carried freely over the vertical faces of a stone at the will of the operator.

2. A stone working machine including a vertical standard and means carried by the standard and including a slideable supporting member movable horizontally inwardly and outwardly, and a tool holding member mounted for free pivotal and slideable movement at the end of the supporting member and provided with means for holding a tool at an angle to it whereby the tool is adapted to be moved freely over the vertical faces of a stone at the will of an operator.

15 3. A stone working machine including a support mounted to oscillate freely on a horizontal axis, a tool carrier consisting of a bar slideable freely in the support at an angle to the axis thereof and provided at the outer 20 end with a head having means for holding a tool at an angle to the said bar whereby the tool may be moved freely at the will of the operator over the vertical face of a stone.

4. A stone working machine including a support mounted to oscillate freely on a horizontal axis, a tool carrier consisting of a bar slideable freely in the support at an angle to the axis thereof and provided at the outer end with a head having means for holding a tool at an angle to the said bar whereby the tool may be moved freely at the will of the operator over the vertical face of a stone.

will of the operator over the vertical face of a stone, and a counter-balancing bar slidably mounted in the support and actuated by the said bar to move the counter-balancing bar 35 in the opposite direction from the tool carrying bar to counter-balance the same in the various adjustments thereof.

5. A stone working machine including a support mounted to oscillate freely on a horizontal axis, a tool carrier consisting of a bar slideable freely in the support at an angle to the axis thereof and provided at the outer end with a head having means for holding a tool at an angle to the said bar whereby the 40 tool may be moved freely at the will of the operator over the vertical face of a stone, a counter-balancing bar also slidably mounted in the support and movable in the opposite direction from the tool carrying bar, said 45 bars being provided at their opposed faces with teeth, and an interposed pinion meshing with the said teeth to cause the tool carrying bar to actuate the counter-balancing bar to counter-balance the tool carrying 50 bar automatically.

In testimony whereof I affix my signature in presence of two witnesses.

GEORGE W. GANTT.
